UNITED STATES PATENT OFFICE.

ROLLIE B. FAGEOL, OF OAKLAND, CALIFORNIA.

DESIGN FOR A MOTOR-DRIVEN VEHICLE.

60,400.

Specification for Design.

Patented Feb. 14, 1922.

Application filed August 24, 1921. Serial No. 495,106. Term of patent 14 years.

To all whom it may concern:

Be it known that I, ROLLIE B. FAGEOL, a citizen of the United States, and a resident of Oakland, county of Alameda, State of California, have invented a new, original, and ornamental Design for a Motor-Driven Vehicle, of which the following is specification, reference being had to the accompanying drawing, forming part thereof.

The figure is a side elevation of a motor driven vehicle embodying my new design.

I claim:

The ornamental design for a motor driven vehicle substantially as shown and described.

ROLLIE B. FAGEOL.
